(57) **CLAIM**

We claim the ornamental design for a vehicle hood, as shown and described.

DESCRIPTION

FIG. 1 is a front perspective view of a vehicle hood showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective enlarged detail view thereof; and,

FIG. 9 is a second front perspective thereof.

Evenly-spaced broken lines depict unclaimed environmental subject matter. Dash-dot broken lines depict unclaimed boundaries of the claimed design.

1 Claim, 9 Drawing Sheets

See application file for complete search history.

Related U.S. Application Data

May 18, 2017, now Pat. No. 10,434,995, which is a continuation of application No. 14/724,279, filed on May 28, 2015, now Pat. No. 9,656,640, which is a continuation of application No. 13/841,686, filed on Mar. 15, 2013, now Pat. No. 9,045,014.
